(57) **CLAIM**

The ornamental design for a wall panel for buildings as shown and described.

DESCRIPTION

The patent or application file contains at least one drawing executed in color. Copies of this patent or patent application publication with color drawing(s) will be provided by the Office upon request and payment of the necessary fee.

FIG. 1 is a plan view of a wall panel for buildings showing my new design; and,

FIG. 2 is an enlarged view of a portion identified in rectangle 2 of FIG. 1.

The broken lines depict the boundaries of the claimed design and form no part thereof.

**1 Claim, 2 Drawing Sheets
(2 of 2 Drawing Sheet(s) Filed in Color)**
